UNITED STATES PATENT OFFICE.

THOMAS DEADERICK, OF NASHVILLE, TENNESSEE.

LOCKING SOCKET FOR ELECTRIC LAMPS.

1,174,233.

Specification of Letters Patent.

Patented Mar. 7, 1916.

Application filed July 15, 1913. Serial No. 779,175.

To all whom it may concern:

Be it known that I, THOMAS DEADERICK, a citizen of the United States of America, residing in the city of Nashville, in the county of Davidson, in the State of Tennessee, have invented a certain new and Improved Locking-Socket for Electric Lamps, of which the following is a specification.

My invention relates to incandescent electric lamp sockets in which provision is made for automatically locking the lamp on its insertion into the socket, and thereby prevent the unauthorized removal of the lamp, while permitting the proper person with a special form of key to release and remove the lamp when desired.

The object of my invention is to provide a simple and inexpensive device of this character, and one which will require the least possible modification of the standard form of lamp socket. This object I attain by the construction which I will now describe.

In the accompanying drawings, Figure 1 is an enlarged view, partly in section, of an incandescent electric lamp socket provided with my improvement; Fig. 2 is a detached outside view of the screw shell of the socket. Fig. 3 is a transverse section through the same looking in the direction of the toothed locking cam; Fig. 4 shows in perspective the locking cam, its spring and the retaining ring, detached.

In these drawings, 10 indicates the ordinary insulating body of porcelain or the like, which carries the lamp and wire terminals, and which may or may not contain suitable switch mechanism. One of the wire terminals is indicated at 11, Fig. 1, while the central lamp terminal is indicated at 12 and the outer lamp terminal is a screw shell 13, adapted to receive and hold the usual threaded base 14 of the incandescent electric lamp 15. The whole is to be inclosed as usual in a metal casing, consisting of a shell 16 and cap 17, both with insulating linings, as usual.

My improved locking device consists of a cam plate 18 with ratchet teeth on its edge and provided with a spindle 19, by which the cam is pivoted in a bearing 20 in the side wall of the screw shell 13, near the base of the shell. The cam plate itself is within the shell so that its toothed face is in a position to contact with the bottom rim of the threaded base of the lamp when the latter is screwed into the socket, as shown in Fig. 1.

The cam spindle is inserted into the bearing 20 from within the shell and is retained in its bearing by the off-set portion 22 of the ring 21, which receives the screws 23, 24, Fig. 3, to secure the screw shell 13 to the insulating body 10. A suitable light spring 24 which may be of any suitable form, but is preferably a coiled spring, such as shown in Fig. 4, is provided to act upon the cam plate 18 in such fashion as to tend to keep the cam plate turned on its spindle to the position shown in Fig. 3. When therefore, a lamp is screwed down into the socket, the rim of the lamp base will contact with the toothed edge of the cam plate and push its projecting end backward, but on attempting to unscrew the lamp out of the socket again, the teeth of the cam plate will bite into the rim of the lamp base and prevent the lamp from being unscrewed, unless the person has the means to free the cam from the lamp base. For this last purpose the outer end of the cam plate spindle is made polygonal, as for example, three-sided as seen in Fig. 2, and a key 25 is provided with a corresponding opening in its end to fit over the polygonal end of the spindle. The handle of the key is made of insulating material, as indicated in Fig. 1, and the shell 16 of the socket is provided with a tubular guide 26 for the key, lined with insulating material and of sufficient length to prevent access to the cam spindle by any other device than a key provided for the purpose.

On applying the key to the spindle 19, and then turning the key against the tension of the spring 24, the cam will be turned sufficiently to free its teeth from engagement with the end of the lamp base, so that then the lamp may be unscrewed and removed from the socket.

I claim as my invention,

1. An electric lamp socket having an insulating body carrying wire and lamp terminals, one of the latter being a screw shell, with a locking cam pivoted in the screw shell to contact with the end of the base to be inserted in the screw shell, said locking cam having means adapted to be actuated by a key.

2. An electric lamp socket, having an insulating body carrying wire and lamp terminals, one of the latter being a screw shell, with a locking cam pivoted in the screw shell to contact with the end of the base to be inserted in the screw shell, a spring to act

upon the cam and a key to move it against the spring.

3. An electric lamp socket, having an insulating body carrying wire and lamp terminals, one of the latter being a screw shell, a locking cam within the shell adapted to contact with the base to be inserted in the screw shell and having a spindle turning in a bearing in the shell, said spindle being adapted to receive and be actuated by a key inserted at the side of the lamp socket.

4. An electric lamp socket, having an insulating body carrying wire and lamp terminals, one of the latter being a screw shell, with a cam plate pivoted in said shell and having a series of teeth on its edge to make contact with the end of the base to be inserted in the screw shell, and a key to actuate the cam plate, the latter having means to receive the key, substantially as described.

5. An electric lamp socket, having an insulating body carrying wire and lamp terminals, one of the latter being a screw shell, with a locking cam having a spindle in a bearing in said shell, the end of the spindle projecting outwardly and adapted to be ac-

tuated by a key, means to hold the spindle in its bearing and a spring to act on the cam, substantially as described.

6. An electric lamp socket having an insulating body carrying wire and lamp terminals, one of the latter being a screw shell with a locking cam within the screw shell and movably mounted therein to contact with the end of the base to be inserted and having means adapted to be actuated by a key.

7. An electric lamp socket, having an insulating body carrying wire and lamp terminals, one of the latter being a screw shell, with a locking cam movably mounted within the screw shell and having teeth to contact with the end of the base to be inserted and having means adapted to be actuated by a key.

In testimony whereof I have signed my name to this specification, in the presence of two subscribing witnesses.

THOMAS DEADERICK.
